UNITED STATES PATENT OFFICE.

HARRY D. HILDEBRAND, OF PITTSBURGH, PENNSYLVANIA.

FLUID-COMPRESSOR.

1,027,841.

Specification of Letters Patent.

Patented May 28, 1912.

Application filed August 7, 1911. Serial No. 642,656.

To all whom it may concern:

Be it known that I, HARRY D. HILDEBRAND, residing at Pittsburgh, in the county of Allegheny and State of Pennsylvania, a citizen of the United States, have invented or discovered certain new and useful Improvements in Fluid-Compressors, of which improvements the following is a specification.

- 10 It is the present practice to arrange the valves both inlet and outlet in the head of the compressor cylinder, and although the valve area is made as large as practicable, it has been found impossible to completely fill 15 the space between the head of the cylinder and the piston during the intake periods, especially when the piston is moving at its highest rate. Similar difficulty as regards a free full discharge of fluid is experienced 20 in the discharge of the air, the pressure in the cylinder rising above normal at or near the middle of the stroke.

The invention described herein has for its object the provision of a larger valve area 25 and preferably one that will increase progressively with the movement of the piston.

The invention is hereinafter more fully described and claimed.

In the accompanying drawings forming a 30 part of this specification, Figure 1 is a sectional elevation of a compressor having my improvement applied thereto; Fig. 2 is a sectional view of one end of the cylinder on an enlarged scale, showing the inlet and outlet valves in section; Fig. 3 is a transverse section on a plane indicated by the line III—III Fig. 1; and Fig. 4 is a view similar to Fig. 2 of a modification of my improvement.

- 40 With an exception hereinafter noted, it has been the practice to arrange the inlet and outlet valves in the heads of the compressor, half of these valves being inlet and half outlet. As the inlet and outlet areas 45 were found to be too small the cylinder heads have been made dome shaped and conical so that a larger number of valves could be employed and in order to avoid clearance the ends of the piston were correspondingly shaped. As the efficiency of the 50 modern steam or gas engine is very largely proportional to the rate of movement of the piston, modern practice demands compressors that can be operated at high speeds. 55 But when the rate is thus increased, it is found that the present valve area is too

small to prevent a drop of pressure below atmospheric as the piston attains its highest rate and a rise above the pressure desired, during the discharge period. In order to overcome this lack of receiving and discharging capacity, inlet or outlet valves, or both inlet and outlet valves are arranged at points intermediate of the ends of the movements of the piston so that said valves or the ports controlled by the valves, will be uncovered during the intake movement of the piston and covered by the compressing and discharge movement.

In the construction shown in Figs. 1 and 2, the heads 1 of the cylinder 2 are made conical and in these heads are mounted valve mechanisms controlling the inlet ports 3 connecting the supply passage 4 with the interior of cylinder, and outlet ports 5 connecting the cylinder with the receiving chamber 6. The mechanism controlling the inlet ports 3 may be, of any suitable construction, as for example, that shown, consisting of a valve 7 adapted to be seated by pressure within the cylinder. This valve is provided with a stem 8 extending outwardly through a shell 9 and having at its outer end an adjustable abutment or bearing 10 for one end of the closing spring 11, the opposite end thereof bearing against a suitable shoulder 12 in the shell 9.

The mechanism controlling the outlet or discharge ports 5 may be of any suitable construction, as for example, that shown. 90 This mechanism consists of a tubular body 13 extending through the outer wall of the receiving chamber 6, and a valve 14 provided with a stem 15 extending into the tubular body which serves as a guide for 95 the valve. This valve is seated against pressure in the cylinder by a spring 16 interposed between shoulders in the stem or valve and the tubular guide.

Experience has shown that during the 100 slow initial movement of the piston from the end of the cylinder, sufficient port area can be provided in the cylinder head to maintain approximately atmospheric pressure in the cylinder. In order to prevent a drop of pressure, or employing valves having a large range of movement, as the speed of the piston increases additional ports 17 are provided in the sides of the cylinder. 105 It will be understood that if one series of 110 these parts will not permit a sufficient inflow of air that one or more additional series

of ports, 17^a, etc., may be employed as shown. It will be observed that during the initial movement of the piston, the ports in the head will be opened by atmospheric pressure and as the piston continues its inward movement the series of side valves are uncovered successively and will permit an increased flow of air. These side ports are controlled by any suitable valve mechanisms 5 as for example, the type herein shown and described. In order to prevent an abnormal increase of pressure during the compressing and discharge movements of the piston, one or more series of outlet ports, 18, 18^a, etc., 10 are formed in the sides of the cylinder, said ports being controlled by suitable valve mechanism preferably of the type shown and described. In thus increasing the port areas, it is possible to employ valve mechanisms 15 having a comparatively small valve movement, thus avoiding the severe hammering action of the valves heretofore used, which were necessarily given a large movement to utilize the entire port area.

20 25 In the construction shown in Figs. 1 and 2, the heads 1 are formed with cylindrical extensions 19 which form the ends of the cylinder proper, and the ports for the inflow and discharge of the fluid are arranged 30 in this extension.

In Fig. 4 is shown a construction having the side ports in the cylinder proper which may be provided with a flat head 1^a.

35 I claim herein as my invention:

35 1. In an apparatus for compressing fluids, the combination of a cylinder, a piston and valve controlled ports located in the wall of the cylinder relative to the movement of the piston so as to be covered by the latter 40 when at the end of its stroke and to be uncovered while the piston is intermediate the

end of its stroke and point of maximum speed.

2. In an apparatus for compressing fluids, the combination of a cylinder, a piston and 45 valve controlled ports located in the wall of the cylinder relative to the movement of the piston so as to be covered by the latter when at the end of its stroke and to be uncovered before the piston has attained maximum speed. 50

3. In an apparatus for the compression of fluids, the combination of a cylinder, a piston, and valve controlled ports, a portion of 55 said ports being adapted to be opened on the initial movement of the piston and a portion subsequent to such initial movement and during the acceleration of the speed of the piston.

4. In an apparatus for the compression of fluids, the combination of a cylinder, a piston, valve controlled ports arranged in the head of the cylinder, and valve controlled ports arranged in the sides of the cylinder 65 the latter being located at points relative to the movement of the piston that they will be covered by the piston when at the end of its stroke and uncovered prior to the piston attaining maximum speed. 70

5. In an apparatus for the compression of fluids, the combination of a cylinder, heads provided with cylindrical portions forming the ends of the cylinder, a piston and valve controlled ports arranged in the ends and cylindrical extensions of the head. 75

In testimony whereof, I have hereunto set my hand.

HARRY D. HILDEBRAND.
